UNITED STATES PATENT OFFICE.

RICHARD WESTERMANN, OF MAGDEBURG, GERMANY.

SPRING HANDLE-BAR FOR CYCLES.

SPECIFICATION forming part of Letters Patent No. 783,162, dated February 21, 1905.

Application filed July 27, 1903. Serial No. 167,192.

To all whom it may concern:

Be it known that I, RICHARD WESTERMANN, locksmith, a subject of the King of Prussia, German Emperor, residing at 6 Stendalerstrasse, Magdeburg, Germany, have invented a new and useful Spring Handle-Bar for Cycles, of which the following is a specification.

The object of the present invention consists of a handle-bar for cycles and like vehicles the object whereof is to prevent the shocks of the machine reaching the hands and arms of the rider. The shocks are not too sensible if the road is in a fairly good condition; but they become tiring by their rapid succession. It very rarely happens that one has to ride along a road in such a bad condition that the motion becomes galloping. It is for this reason that the spring must easily move about its position of rest. Contrarily, the resistance of the spring should increase very rapidly when the amplitude of the trepidation increases. The handle-bar also should be disposed so that it can furnish a rigid fulcrum when the rider increases his speed and for that purpose increases the pressure of the feet upon the pedals by a traction exerted by the arms and hands upon the handle. These advantages are obtained by the disposition hereinafter set forth, and represented by way of example in the annexed drawings, in which—

Figure 1 is a longitudinal vertical section of this invention. Fig 2 shows a horizontal section of same. Fig. 3 shows a horizontal section thereof, the spring being arranged in a slightly-different manner.

The novelty consists, essentially, in the disposition of the springs submitted to the efforts of torsion and in the special manner of connecting together the parts influenced by the springs.

a indicates the tube of the handle-bar, which is cut at the center, projects outwardly, and is terminated with two handles. The two parts are connected together by a short tube *b* and can turn in the horizontal portion of the head of the handle-bar *c*. The tube *d* enters in the usual manner into the front-fork

tube and is solidly connected thereto. The ends of the tube *b* are furnished with metal plugs *e*, connected, by means of screws or rivets *f*, to the handle-bar and to the portion *b*. These metal plugs grip at the same time the torsion-spring *g*, so as to compel the spring to follow the rotation of the handle-bar.

The spring *g* is preferably composed of a certain number of separate springs, which may be flat and bear one upon the other, Figs. 1 and 2. These springs may also have a round, square, or other similar section. In the latter case they are arranged in groups, Fig. 3.

A metal part *h* is slid over the springs *g* and in such a way that at the center it is between the two metal bungs. This part firmly holds the springs and has a small amount of play inside the tube *b*.

The metal part *h* is provided with a hole passing from one side of it to the other and is provided with a bolt *i*, which passes through the two sides of the tube *b*, as well as through the tube of the handle-bar *a*, by means of holes slightly larger than its own diameter. The projecting ends of the bolt *i* are fixed inside the head *c* of the handle-bar. Owing to this disposition, the spring is maintained immovable by its center. If from thence the handle-bar is moved upwardly or downwardly by its free and curved ends, the rotation of the straight portion situated inside the head *c* of the handle-bar is transmitted, by means of the intermediate tube *b* and metal plugs *e*, to the spring *g*, which consequently must follow this rotary motion and are twisted. As the springs are fixed at *h* and at *e*, the different parts of the spring are submitted to both the tractional and bending efforts, thereby causing the resistance of the spring which at first was weak to increase very rapidly. The limit for the rotation of the handle-bar is reached when the edges of the holes in *a* and *b* bear against the bolt *i*.

What I claim as my invention, and desire to secure by Letters Patent, is—

In a spring handle-bar having a fixed middle part and two outer parts socketed into the middle part, a short tube joining the halves

of the handle, a drum in midst of same, a
spring device, comprising a number of flat
springs penetrating the drum, a screw-bolt
piercing drum and springs at once, plugs fixed
5 at the ends of said tube penetrated by the
spring device and firmly joined to it, all as
described and for the purpose set forth.

In witness whereof I have hereunto set my
hand in presence of two witnesses.

RICHARD WESTERMANN.
